(57) **CLAIM**

We claim the ornamental design for a sleeve for a container, as shown and described.

DESCRIPTION

FIG. 1 is a top, left perspective view of a sleeve for a container, showing my new design;

FIG. 2 is a bottom, right perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines on the sleeve for a container depict portions that form no part of the claimed design.

The container shown in broken lines represents environment only and forms no part of the claimed design.

1 Claim, 7 Drawing Sheets
